[57] **CLAIM**

The ornamental design for combined lens and tracking indication light in a personal location unit, as shown and described.

DESCRIPTION

FIG. 1 is a front perspective view of a combined lens and tracking indication light in a personal location unit showing my new design;

FIG. 2 is a left end view thereof;

FIG. 3 is a side elevation thereof; the opposite side being a mirror image thereof;

FIG. 4 is a right end view thereof;

FIG. 5 is a top plan view thereof;

FIG. 6 is a bottom view thereof;

FIG. 7 is a perspective view of a second embodiment thereof;

FIG. 8 is a left end view thereof;

FIG. 9 is a side elevation thereof; the opposite side being a mirror image thereof;

FIG. 10 is a right end view thereof;

FIG. 11 is a top view thereof; and,

FIG. 12 is a bottom view thereof.
